TABLE KNIFE

Oliver Messel, 17 Pelham Place, London, England

Filed June 1, 1964, Ser. No. 80,210

Term of patent 14 years

(Cl. D22—3)

FIG. 1 is a top plan view of a table knife showing my new design;

FIG. 2 is a left side elevational view thereof; and

FIG. 3 is an enlarged sectional view taken along the line 3—3 of FIG. 1.

I claim:

The ornamental design for a table knife, substantially as shown.
